Patent No. 2,477,141, issued July 26, 1949, to Willard M. Pollock, Glen Ellyn, Ill., for an improvement in ink fountain adjustment means for rotary printing presses, serial No. 613,904, filed August 31, 1945.

UNITED STATES PATENT OFFICE

2,477,141

INK FOUNTAIN

Willard M. Pollock, Glen Ellyn, Ill., assignor to
The Goss Printing Press Company, Chicago,
Ill., a corporation of Illinois

Application August 31, 1945, Serial No. 613,904

2 Claims. (Cl. 101—365)

1

This invention relates to ink shutoff means for rotary printing presses and refers more particularly to a combination page and column ink adjustment comprising means for shutting off page widths of ink from the fountain roller from stations positioned within the respective page widths along the roller, and means located operatively between the page shutoff and the roller for partially shutting off ink from column widths of the roller, the column adjustment means being controlled from a common station by warped rods loosely journaled so as to maintain any rotational position to which they may be set.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings,

Figure 1 is a top elevation, partly broken away, of a device embodying the invention;

Figure 2 is a side elevation of the same taken along the line 2—2 of Figure 1;

Figure 3 is a section along the line 3—3 of Figure 1;

Figure 4 is a section along the line 4—4 of Figure 2; and,

Figure 5 is a section along the line 5—5 of Figure 3.

The present invention has for its object the provision of a quicker and more convenient shutoff and adjusting means for the ink fountain of a printing press. A further object is the provision of separately operable means for page shutoff and column adjustment. A further object is the provision of a central station controlling all the column adjustments. A further object is the provision of column adjusting actuating means terminating in a central station and adapted to retain their respective setting without further attention from the operator. A further object is to provide a page shutoff which on being released restores the previously existing column adjustment. Other objects will become apparent in the course of the following specification.

2

In accordance with the illustrative embodiment of the present invention there is provided a doctor blade carrier capacitated to carry a doctor blade, preferably of page width, in operative relation to the fountain roll. The rear edge of the doctor blade is affixed to the carrier in conventional manner. The carrier has a longitudinal channel into which open a plurality of bore holes the axes of which are slightly inclined from the vertical. Cylindrical nuts with square heads engaging the channel walls are slideable in the bores, and into each is threaded a screw, each screw being adapted to engage the doctor blade and depress same for columnar ink adjustment. The upper ends of the screws are unthreaded and slide in bores formed in a pivot bar in the carrier unit. Substantially coincident longitudinally with the doctor blade is the page shutoff board, comprising a parti-cylindrical lip engaging a corresponding channel extending longitudinally of the pivot bar and in the upper forward corner of the carrier viewed in cross section, this channel being open downwardly and rearwardly. The page shutoff board extends rearwardly from this channel to engage the column adjusting screws, and is adapted to depress them by pivoting around the axis of the channel. Downward pivotal motion is imparted to the board by an arm extending to the rear of the carrier and connected to a spring loaded plunger which is actuated by a manually operated cam lever pivoted in the carrier frame. Screws are threaded into the board and extend from the bottom surface thereof to engage the column adjusting screws. The bodies of the latter carry worm gears which are engaged by suitably supported worms on the ends of rods, all of the rods associated with one page extending in the same direction from their respective worms and terminating in squared ends supported in and extending through a common control plate. The rods are flexible and are maintained in a warped condition in loose bearings.

It is evident from the above that the pressman standing at the control plate may regulate the ink supply to each column served by the fountain by turning the squared end of the rod connected to the respective adjusting screw, and that the setting of each screw will be maintained by the frictional engagement of the elements of the worm and gear and the warped rod in its loose bearings. The loose bearings, which may be mere drilled plates, are desirable for their simplicity and economy. The page shutoff is accomplished by movement of the cam lever, which depresses the shutoff board, depressing all the column ad-

justing screws on that page. An advantage of this mechanism is that on return of the shutoff lever to inoperative position the column adjustment setting of the doctor blade previous to shutting off the page is restored automatically.

It will be understood that the foregoing general description and the following detailed description as well are exemplary and explanatory of the invention but are not restrictive thereof.

Referring now in detail to the illustrative embodiment of the invention as shown in the drawings, the press frame 10 supports the ink fountain frame 11, in which are located fountain roller 12 and ductor roll 13, all in conventional manner. The fountain blade 14 is supported in operative relationship to the fountain roller 12, being affixed along its rear edge to the blade carrier 15 which is mounted on standards 16 on the fountain frame 11. Doctor fingers 17 project from the operative edge of the doctor blade 14 to scrape the ink from the ends of the fountain roller 12. As illustrated, the doctor blades 14 are of page width, and the blade carrier 15 will be of sufficient length to carry the desired number of blades.

The carrier 15 is of substantially rectangular cross section, and comprises a trough shaped body 18 formed with a longitudinal groove 19 extending along the exterior front portion of the floor 20 thereof. A plurality of cylindrical bore holes 21 open into groove 19 and in these holes 21 cylindrical square headed nuts 22, locked against rotation by engagement of their heads with groove 19, slide slantingly down from the position shown and back again. Column adjusting screws 23 are threaded into nuts 22 and engage blade 14.

Pivot bar 24 is affixed to the upper front corner of carrier body 18 interiorly and longitudinally thereof, and is formed with a parti-cylindrical longitudinal pivot channel 25 opening inwardly and downwardly. Pivot bar 24 also comprises an inwardly extending ledge 26 in which the unthreaded upper portions of screws 23 are bushed.

Intermediate portions of screws 23 carry worm gears 27 fixed thereto and axially fixed, rotatable yoke collars 28, of which the collar portions 29 surround screws 23 and the yoke portions 30 support rods 31 and worms 32 carried thereby.

The page shutoff board 33 is preferably long enough to engage the column shutoff screws 23 of a page, and comprises a parti-cylindrical lip 34 seated in pivot channel 25. Equalizer screws 35 are threaded through board 33 to contact the upper ends of column shutoff screws 23, and are furnished with jam nuts 36. Page shutoff arm 37 extends rearwardly from board 33 substantially to the outside rear surface of carrier body 18.

A thickened portion 38 of the rear wall of carrier body 18 is formed with a stepped bore 39 in which is located a plunger 40 which extends through arm 37. A compression spring 41 coiled about plunger 40 engages arm 37 and actuates same toward the head 42 of the plunger. To the bottom end of plunger 40 is pivotally attached by pin 43 the cam lever 44, comprising handle 45 and cam surface 46, 47 which engages race 48 constituted by the bottom surface of the thickened portion 38.

Rods 31 are warped backwardly from their respective yokes 28 to angle plate 49 screwed to the rod housing 53, and after passing through holes 50 in plate 49 constituting loose bushes or

bearings, are warped upwardly to and through similar loose bush holes in index plate 51 which may be inclined so that its outer face is more accessible from above and which may further bear suitable indicia indicating the column adjusting screws 23 to which the respective rods 31 are connected. The ends 52 of rods 31 may be squared or otherwise formed to receive a tool for imparting rotary motion. The housing 53 extends laterally of the press from blade carrier 15 to index plate 51 and is closed by a removable top cover 54.

In operation, column adjusting screws 23 may be set for individual column adjustment according to known practice by rotating the squared ends 52 of rods 31 from the central station or index plate 51, the worms 32 on the opposite ends of the rods acting on worm gears 27 to rotate screws 23 to advance or retract them in the nuts 22. The latter are fixed against upward movement by their heads engaging the shoulder of groove 19, advancing a screw 23 in a nut 22 serves to depress the underlying portion of fountain blade 14 for column adjustment. When the column settings of a page have been made, equalizer screws 35 are adjusted to contact the upper ends of screws 23 and locked in position by jam nuts 36, page shutoff board 33 being in the full line inoperative position illustrated.

Page shutoff is accomplished by moving handle 45 of cam lever 44 to the broken line position, whereby the plunger 40 is depressed by the ambulatory pivot pin 43 actuated by the action between cam surfaces 46, 47 and race 48. Plunger 40 carries the rear end of arm 37 with it resulting in page shutoff board 33 pivoting downward about the axis of lip 34 and pivot channel 25. All the column adjustment screws 23 of the page thereupon move downward, actuated through screws 35 and sliding in the bushes of ledge 26 and carrying the nuts 22 with them. The page width of fountain blade 14 is thus cut off. On return of handle 45 to the full line position, arm 37 is returned to full line position by spring 41 and doctor blade 14 returns screws 23 to the exact position they held before page shutoff.

There is thus provided an ink fountain adjustable for column setting from a central station by means of very simple construction and which is further adapted to maintain any setting without the use of separate or subsequently operated locking devices. The fountain further provides page shutoff which is operable without destroying column adjustment settings, the former means operating through the latter means and leaving the latter means in its previous position upon the former becoming inoperative.

The invention in its broader aspects is not limited to the specific mechanisms shown and described but departures may be made therefrom within the scope of the accompanying claims without departing from the principles of the invention and without sacrificing its chief advantage.

What is claimed is:

1. Printing press ink shutoff means comprising the combination with a fountain blade, a fountain blade carrier and column adjusting screws, of nuts slidable in said carrier and threaded to receive said screws, said carrier comprising a portion formed with a parti-cylindrical pivot channel formed therein and extending longitudinally of said carrier, a page shutoff board comprising a

parti-cylindrical lip corresponding to and extending into said channel, equalizing means mounted on said board and adapted to contact said screws, and means for depressing said board for page cut-off or the like.

2. Printing press ink shutoff means comprising the combination with a fountain blade, a fountain blade carrier and column adjusting screws, of nuts slidable in said carrier and locked against rotation therein and threaded to receive said screws, said carrier comprising a portion formed with a parti-cylindrical pivot channel formed therein and extending longitudinally of said carrier, a page shutoff board comprising a parti-cylindrical lip corresponding to and extending into said channel, equalizing means mounted on said board and adapted to contact said screws, said carrier comprising a rear wall comprising a thickened portion comprising a lower surface constituting a cam race, said portion further being 10 formed with a stepped bore, a headed plunger

slidable in said bore, a compression spring surrounding said plunger in said bore, an arm firmly connected to said board and having an opening through which said plunger extends, said arm being engaged on opposite sides by said plunger head and said spring, and a cam lever pivotally connected to the lower end of said plunger and having cam surfaces engaging said race.
